UNITED STATES PATENT OFFICE.

JOHN E. BELL, OF BROOKLYN, NEW YORK.

CEMENT-KILN PLANT AND METHOD OF OPERATING THE SAME.

1,393,738.

Specification of Letters Patent.

Patented Oct. 18, 1921.

Application filed August 2, 1918. Serial No. 247,923.

To all whom it may concern:

Be it known that I, JOHN E. BELL, a citizen of the United States of America, and resident of Brooklyn, in the county of Kings 5 and State of New York, have invented a certain new and useful Improvement in Cement-Kiln Plants and Methods of Operating the Same, of which the following is a true and exact description, reference being 10 had to the accompanying drawings, which form a part thereof.

My present invention comprises improvements in the construction, arrangement and method of operating cement kiln systems in 15 which the hot gases leaving the cement kilns are passed through so-called waste heat boiler furnaces in which the heat contained in the gases is partially absorbed and utilized. My invention relates particularly 20 to a system in which a plurality of rotary cement kilns are used. The general object of the invention is to provide a plant construction and arrangement and method of operating same which will be simple and reliable, 25 and will give a desirably high efficiency without entailing prohibitive costs of installation, operation and maintenance.

The heating of steam generating boilers by the hot gases leaving industrial furnaces 30 of many kinds, including rotary cement kilns, has been often proposed, and has been practised with success in some instances, but the effective utilization of the heat contained in the hot gases issuing from rotary 35 cement kilns presents special difficulties, and so far as I am aware no satisfactory plan of utilizing the gaseous products from a battery of rotary cement kilns in heating steam generating boilers has been developed 40 prior to my present invention.

The special difficulties standing in the way of the effective utilization of the hot gases from rotary cement kilns in waste heat boiler furnaces include or arise from various 45 factors or circumstances. There are usually several rotary cement kilns in each battery or unit, the average number of kilns in each such unit in this country being perhaps six or seven. The volume of heated gas issuing 50 from each kiln is relatively large. The volume of gas and the frequent necessity for cutting out portions of the plant for cleaning and repairs, as well as on account of irregularities in the output capacity required, make it desirable to associate with 55 each battery of kilns a plurality of waste

heat boiler units. Practical operating considerations make it necessary that the plurality of kilns for each unit or battery, and the corresponding waste heat boilers, be connected by a common flue system, so that any one kiln or any one boiler furnace may be cut out of service without necessarily interfering with the operation of the rest of the system. The hot gases leaving the cement 60 kilns carry with them a relatively large amount of flue dust, consisting mainly of particles of the finely ground stone from which the cement is made, and both the amount of this dust, and the difficulties to 65 which it gives rise, are augmented by the fact that the draft must be ample to give a high velocity of gas flow past the heat absorbing surfaces of the waste heat boiler portion of the system, this high velocity being 70 necessary to insure a desirably high operating efficiency. The draft loss, or drop in pressure head, in the kilns proper is comparatively small and forms but a small fraction of the total draft or drop in pressure 75 head necessary to move the burning gases and products of combustion through the system as a whole. This makes it difficult to obtain, and to preserve under the varying conditions of operation, the necessary substantial 80 uniformity of draft in the different kilns. The relatively large total draft required and the relatively high temperature, ordinarily about 1500° F., at which the hot gases leave the kilns, makes it both difficult 85 and especially important to keep the air leakage into the flue system at a practical minimum because of the injurious effect on the plant efficiency of such leakage. The leakage itself works against the efficiency in 90 two ways; it increases the draft consumption and thereby increases the difficulty of maintaining the proper draft, and by lowering the temperature of the heated gases, it materially and directly reduces the efficiency 95 of the waste heat utilizing apparatus.

The specific object of the invention may be said to be such a construction and method of operating a cement kiln system comprising a plurality of kilns and a plurality of 100 waste heat boiler furnaces, that the proper draft conditions may be maintained in the various kilns and in the various waste heat boiler furnaces by means of a common collecting and distributing flue system of such 110 character as to facilitate the temporary cutting out of service of an individual kiln or

boiler furnace, and without an undesirably large loss of efficiency due to heat radiation from the flue system or air leakage into the same, and without entailing a prohibitively high cost of construction, maintenance and operation.

The various features of novelty which characterize my invention are pointed out with particularity in the claims annexed to 10 and forming a part of this specification. For a better understanding of the invention, however, and the advantages attending it reference should be had to the accompanying drawings and descriptive matter in 15 which I have illustrated and described preferred constructions and methods of operation embodying my invention.

Of the drawings:

Figure 1 is a somewhat diagrammatic plan 20 with parts broken away and in section of a cement kiln system constructed in accordance with the present invention.

Fig. 2 is a partial section on the line 2—2 of Fig. 1.

Fig. 3 is a partial section on the line 3—3 of Fig. 1.

Fig. 4 is a section on the line 4—4 of Fig. 1.

Fig. 5 is a view taken similarly to Fig. 1 30 illustrating a modified system.

Fig. 6 is a section on the line 6—6 of Fig. 5.

Fig. 7 is a view taken generally similar to Fig. 1 illustrating a third construction.

Fig. 8 is a partial section on the broken 35 line 8—8 of Fig. 7.

In the system illustrated in Figs. 1 to 4, inclusive, there are seven rotary cement kilns A of ordinary construction, and each adapted to discharge the heated gases issuing from its upper end into a common collecting or bus channel E, which also serves to supply heating gases through branches E' to three separate steam generating boiler furnaces F. 40 As shown, the upper or discharge end of each of the slightly inclined kilns A opens directly into an individual chamber or kiln head B. Each kiln head B may discharge either through a port C' into the base of a corresponding individual stack C, or through a passageway D into the common or bus channel E. Provisions are made for effecting a removable closure of each of the two outlets from the chamber B, since ordinarily one of 45 these outlets must be closed when the other is open. The removable closure for the stack connection is formed, as shown, by means of removable closure bars C² disposed to cross a restricted portion C³ of the stack, preferably located immediately above the top of the port C'. It is not necessary to describe this closure in detail since its specific construction forms no part of the present invention and is fully disclosed, moreover, in 55 my Patent No. 1,311,435, granted July 29,

1919. The passage D, leading from each chamber B to the bus channel E is shown as generally horizontal, but is formed with its bottom wall in two portions which are inclined downwardly away from the opposite 70 sides of a restricted throat portion of the channel. A kerf D', formed in the wall of the channel D, at its throat portion, is normally filled by a U shaped body J when flow through the passage D is permitted, and 75 when flow through the passage D is cut off, the kerf D' is filled by the edge of a plate like damper or cut-off which then extends across the throat portion of the channel, as shown at JA in Fig. 6. The member J may 80 be proportioned and arranged to partially obstruct and thus further restrict the throat portion of the corresponding passage D when this is desirable. The joints between the side walls of the kerf and the member, J or 85 JA, filling the kerf are normally sealed by luting them with clay. This special construction of damper or cut-off valve while novel with me is not claimed herein, but is disclosed and claimed in my Patent 1,311,436, 90 granted July 29, 1919. The restriction of the 95 passages D at their throat portions insures a high gas velocity through the throat portions, preventing flue dust from lodging in these restricted portions, and the inclination of the portions of the bottom wall of each passage D at each side of the throat, minimizes the accumulation thereon of flue dust. The shape and capacity of the lower portions of the chambers B are such as to permit considerable accumulations of flue dust therein without interference with the operation of the system, and these accumulations can be removed from time to time through suitably disposed cleanout doors (not shown). The 100 restriction of each passage D at its throat exerts an important influence on the draft conditions, and the extent to which the throat is restricted depends upon the draft controlling effect desired as is hereinafter 105 explained.

The bottom wall of the channel E is inclined so that the flue dust deposited thereon tends to go to one lower corner of the channel at which open distributed inlets I' to dust 115 removing conveyer pipes I running along the bottom of the channel. The passages E' by which the channel E is connected to the different boiler furnaces proper are each formed with a kerf E² in its wall to receive a cut-off damper E²⁰. The joints between the side walls of the kerf E² and the damper or cut-off valve E²⁰ are preferably sealed by luting them with clay. As shown, each boiler furnace is formed with four passes for the heating gases. These passes are traversed by the water tubes of a water tube boiler of ordinary construction, provided with superheating tubes F'. F² represents normally closed 120 cleanout doors at the bottom of the furnace. 130

Each boiler furnace is provided with an individual draft producing fan H, and interposed between each boiler furnace and the corresponding fan is an economizer or feed water heater having its tubes transverse to the general direction of flow of the heating gases. G' represents cleanout doors for the removal of flue dust from the bottom of the economizer. The walls of the flue system connecting the different kilns A, to the different boiler furnaces F, must be lined with refractory material to withstand the high temperatures of the gases passing through them, and are advantageously formed with a relatively impervious and heat insulating jacket around a fire brick lining in order to reduce heat radiation loss and leakage of air into the flue system.

The clinker forming material, or finely crushed cement forming stone, is fed into the upper ends of the various kilns A by corresponding conveyer pipe portions K, arranged to pass one through each of the chambers B into the corresponding open kiln end. The fuel, which may be coal, gas or oil for heating the kiln, and the air for supporting its combustion, are fed into the ends of the kilns remote from the chambers B, and regulated in the usual manner, which, as it is well known, need not be illustrated or described herein.

In the operation, the hot gases issuing out of the upper end of each of the kilns A pass into the corresponding chambers B at a temperature of about 1500° F. From each chamber B the gases pass through the port C' to the corresponding stack C, when the passage D is closed, or in the more normal condition when the stack C is sealed, they pass through the then open passage D into the bus channel E. The gases flow through the channel E to the outlets E' through which that channel communicates with the different furnace chambers F. The gases passing out of the channel E, through each passage E', flow through the corresponding boiler furnace F and economizer G to the corresponding fan H, which discharges the cooled gases either directly into the atmosphere, or into a suitable discharge stack or conduit not shown. In any event the fans H create the draft relied upon to carry the burning gases and products of combustion through the kilns, the flue system connecting the kilns to the boilers, and through the latter and the economizers G. The effective abstraction of heat from the gases requires a comparatively high velocity of flow of the gases over the heating tubes of the boiler and economizer. To obtain this the boiler and economizer tubes should be closely spaced, and the high velocity of flow, coupled with the restricted and tortuous character of the boiler and economizer flow paths, result in a substantial loss of pressure head or draft consumption in this portion of the apparatus. This high gas velocity is also desirable to minimize the lodging of flue dust on boiler and economizer tubes. The bores of the kilns A are straight and large in diameter and on this account offer little resistance to the flow of the burning and heating gases through them. In consequence the draft consumption in the kilns is relatively small, and slight fluctuations in the pressure at the discharge end of a kiln produces a substantial and highly undesirable variation in the amount and character of the combustion in the kiln. In the channel E there is a considerable longitudinal flow which varies at different points owing to the distributed in-flow into this channel from the different kilns, and this variable longitudinal flow creates differences in static pressure at different points along the length of the latter, which react upon the draft through the different kilns and tend to make the draft conditions in the different kilns unequal. With the longitudinal flow in the channel E toward the end of the channel to which the furnaces F are connected the static pressure at that end of the channel must be lower than it is at the end of the channel remote from the furnaces. Furthermore, the effect of friction and the increase in velocity of flow as the furnaces are approached, due to the distributive admission into the channel E along its length from the various kilns A, both tend to increase the difference between the static pressure at the end of the channel E to which the furnaces F are connected and the opposite end of the channel. The disturbing effect of the change of velocity and the friction loss in the channel E may advantageously be compensated for to some extent by making the cross section of the channel increase as the end of the channel to which the furnaces F are connected in approached; and in Fig. 1 I have shown the section of the conduit E into which the four kilns nearest the furnaces open larger in cross section than the section into which the other three kilns open. Practical pressure equilibrium cannot be obtained by this expedient, however, even with all of the kilns continuously in regular operation. Moreover, any such approach to equilibrium as could be obtained under steady operating conditions, by thus varying the cross section of the channel E, would be destroyed, in practical operation, by disconnecting any particular kiln A from the channel E. The variations in static pressure in the channel E could be made desirably small, of course, by simply making the channel E very large in cross section, but this is not practically feasible because of the increase in cost of construction in heat radiation, and in liability to the influx of air, resulting from a great increase

in the size of this channel, and in many cases space conditions would themselves make such an enlargement in the cross section of the channel E practically impossible 5 of attainment.

I have discovered, and the essence of my invention, in its broader aspects, lies in this, that the disturbing effects in the kiln draft, due to variations in static pressure in a bus 10 channel E of moderate and suitable dimensions, may be reduced to an extent not seriously objectionable by the simple expedient of restricting the passages D connecting the kilns to the bus channel E, so that the drop 15 in pressure, or draft consumed by the hot gases in flowing through these passages becomes substantially larger than the loss of pressure or draft consumption in the individual kilns, and larger than the fluctuations 20 in pressure in the bus channel E.

For example, with such an arrangement as is illustrated in Fig. 1, the variation in static pressure between the points in the channel E adjacent the ends of the two kilns 25 most remote from one another would be in practice something like .2 of an inch of water. The draft or pressure loss in each kiln would be in the neighborhood of .2 or .3 of an inch of water. Assume that the loss 30 of head in the bus channel is only .1 of an inch of water and the effective kiln draft is .2 of an inch of water, then if the kilns were in unrestricted communication with the channel E, and the pressure in the channel 35 E was such as to create the proper draft of .2 of an inch through the kiln A, nearest the furnace F, the draft through the kiln most remote from the furnaces F would be only .1 of an inch of water. The gas flow through 40 the different kilns is proportional to the square root of the effective draft, and in the instance just cited the end kilns would vary in capacity as the square root of .1 is to the square root of .2, which means that the flow 45 through the kiln closest the furnaces would be more than 40% greater than the flow through the kiln most remote from the furnaces. By restricting the connection between the kilns and the channel E so that 50 the draft consumed by the passage of the normal amount of gas through each of these restricted portions would be say .3 of an inch, then the actual capacity of the two end flues would be in the ratio of the square root 55 of .4 to the square root of .5, and the capacity of the flue nearest the furnace would then be only about 12% greater than the capacity of the more remote flue. By increasing the pressure drop through the restricted 60 connections between the kilns and furnaces to an inch of water the change in capacity could be brought down to less than 5%. Practically a variation in draft of 5%, or even 10%, is not highly objectionable, as 65 such a draft variation can be compensated

for, to a substantial degree, by adjustment of the air and fuel admission inlets to the remote ends of the kilns.

No provisions for varying or adjusting the restrictions or throttling effect afforded 70 by the restricted portions of the various passages D need be provided, in some cases, though where the passages D are throttled more or less, under different operating conditions as by means of dampers J partially 75 obstructing the passages D, it is possible to obtain the desired draft equalization with a somewhat smaller total draft than is required when the throttling effects, due to the restricted dimensions of the permanent walls 80 of the throat portions of the passages D, are wholly relied upon. The effect of throttling communication between the various kiln heads and the common collecting flue E is, of course, to increase the total draft re- 85 quired. The production of the extra amount of draft thus entailed is ordinarily not a serious matter. The extra draft does, of course, increase the tendency to air leakage, but it is to be noted that this tendency to in- 90 creased leakage only exists with respect to the portions of the flue and furnace system at the outlet sides of the kiln heads B, and does not exist in the kiln heads proper, where, because of the necessity of providing 95 for the necessary motion of the kilns with respect to the kiln heads, it is most difficult to guard against leakage.

While changes in the static pressure in the portion of the conduit to which the different boiler furnaces E are connected tend to disturb the distribution through the boiler furnaces, the disturbance in this case is much less serious than in the case of the kilns and can moreover be adequately compensated for 100 by varying the speed of operation, and hence the draft producing effects of the different fans H when each boiler furnace is provided with an individual fan. Where the arrangement of the furnace system is 110 such as to minimize the static pressure variations at the inlets to adjacent waste heat boiler furnaces, as is the case with the arrangement shown in Figs. 5 and 6, it is not practically necessary to provide an individual fan for each waste heat unit, and in 115 Fig. 5 one pair of adjacent waste heat units F at the left of the figure are shown as provided with a common exhaust fan.

The desirability of regulating draft conditions by throttling communication between the various kilns and the flue system into which they discharge is augmented by the fact that where the invention is used in connection with waste heat recovery systems added to existing installations, as well as in wholly new installations, a great variety of arrangements of kilns, boilers and connecting flues must be employed. Thus Figs. 1 and 5 show plants differing mate- 120 125 130

rially from one another in their general layout, while Figs. 7 and 8 show a third arrangement differing from the first two. In Figs. 7 and 8 the collecting flue E extends over the kilns A, and the connections D to the kiln heads B, are at the same side of the latter, as are the kilns A; this arrangement being made necessary by the fact that space in direction of the length of the 10 kilns is especially restricted. On account of the diversity in the plant layouts, which must be adopted in different cases, it is especially difficult to attempt to approximate static pressure equalization in the collecting 15 flue by tapering the latter, since the amount of taper which will give the best practical results cannot be theoretically determined, but must be determined experimentally or be based upon past experience. It will be 20 understood, of course, that the three different layouts illustrated, while typical, represent by no means the various forms or kinds of arrangement which must be employed in practice.

25 While in accordance with the provisions of the statutes I have illustrated and described the best structural embodiments of my invention, and the best modes of practising it now known to me, those skilled in 30 the art will understand that changes may be made in the form of the apparatus, and method of operation disclosed, without departing from the spirit of my invention as set forth in the appended claims. Those 35 skilled in the art will also understand that certain features of my invention may sometimes be used with advantage without a corresponding use of other features.

Having now described my invention, what 40 I claim as new and desire to secure by Letters Patent, is:

1. The method of operating a cement kiln plant comprising a plurality of rotary cement kilns, a waste heat boiler section and 45 a flue into which the individual kilns open at points at varying distances from the boiler section, and which connects the series of kilns to said boiler section which consists in throttling the connection between each kiln 50 and the flue to such an extent as to make the pressure drop or draft consumption between each kiln and the flue greater than the total pressure drop or draft consumption in the flue and maintaining such draft conditions 55 throughout the connected parts of the system as will compensate for the resistance created by the throttling of said connections and bring about a sufficient and an approximately even draft in the kilns.

60 2. In a cement kiln plant comprising a series of rotary cement kilns, a collecting flue, one or more waste heat boiler sections connected to the flue and a series of connecting flues leading from the kilns to the collecting flue at points at varying distances from the

boiler connections, the construction of the collecting flue and of the connecting flues from the kilns of such normal fixed proportions relative to each other that the loss of pressure head in each said connecting flue is 70 greater than the loss of pressure head in the collecting flue and the draft in the kilns thereby maintained at such approximation to uniformity as is necessary for their effective working.

75 3. In a cement kiln plant comprising a series of rotary cement kilns, a collecting flue, a plurality of waste heat boiler sections connected to the flue at different points along its length and each provided with an independent suction fan to induce draft therein and a series of connecting flues leading from the kilns to the collecting flue at points at varying distances from the boiler connections, the construction of the collecting flue 80 and of the connecting flues from the kilns of such normal fixed proportions relative to each other that the loss of pressure head in each said connecting flue is greater than the loss of pressure head in the collecting 85 flue and the draft in the kilns thereby maintained at such approximation to uniformity as is necessary for their effective working.

4. In a cement kiln plant comprising a series of rotary cement kilns, a collecting flue, one or more waste heat boiler sections connected to the flue, a series of connecting flues leading from the kilns to the collecting flue at points at varying distances from the boiler connections and gates for closing each 95 connecting flue at will, the construction of the collecting flue and of the connecting flues from the kilns of such normal fixed proportions relative to each other that the loss of pressure head in each said connecting flue is greater than the loss of pressure head in the collecting 100 flue and the draft in the kilns thereby maintained at such approximation to uniformity as is necessary for their effective working.

105 5. A cement kiln plant comprising a series of rotary cement kilns, a flue or chamber for each kiln into which it delivers its gas, a stack leading from each chamber, a common collecting flue, one or more waste 110 heat boiler sections connected to the collecting flue, connecting flues leading from the stack chambers to the collecting flue and entering the same at varying distances from the points where the boiler sections connect therewith, each of said connecting flues having such normal restricted and fixed areas as will bring about a pressure drop therein in excess of the pressure drop in the collecting flue and thereby insure an approximation to 115 uniform draft in the kilns, and valves whereby the gases from the kilns can be directed to the stacks or collecting flues at will.

120 6. A furnace system comprising a plural- 130

ity of rotary cement kilns, a stack and flue connection to said stack for each kiln, a collecting flue and waste heat boiler section connected thereto, a connecting flue from each kiln to the collecting flue and valves for directing the gases from each kiln to its stack or connecting flue at will, said connecting flues leading to the collecting flue being structurally of such fixed restricted

area with reference to the area of the kilns 10 and collecting flue that the loss of pressure head in each such connecting flue is greater than the loss of pressure head in the kiln and collecting flue, and said collecting flue having an inclined bottom and a dust collect- 15 ing chamber connecting therewith.

JOHN E. BELL.
